LEATHER SHAVING MACHINE

Filed Aug. 9, 1929

UNITED STATES PATENT OFFICE

FRANK WAYLAND, OF SALEM, MASSACHUSETTS

LEATHER SHAVING MACHINE

Application filed August 9, 1929. Serial No. 384,635.

This invention pertains to leather shaving machines of the kind employed in tanning and other leather working establishments, and relates more particularly to improved 5 means for supporting and controlling the bed or feed roll of such a machine.

Machines of this type usually comprise a rotating shaving knife or cutter and a feed roll which is bodily movable toward and 10 from the cutter, and which is adapted to press the work into contact with the cutter blades. In accordance with the usual practice, the operator endeavors to save as much weight in the hide or skin as possible, and 15 thus shaves off only such portions of the skin as are unfit for use, shifting the hide over the feed roller between successive engagements with the cutter, and when so shifting it relieving the pressure between the 20 roll and cutter. To facilitate this non-uniform shaving, the bed or feed roll is actuated by a treadle upon which the operator rests so much of his weight as is necessary to obtain the desired depth of cut at any given 25 spot, the pressure upon the treadle being the determining factor at all times which controls the operation of the knife upon the hide or skin. In accordance with certain 30 modern practices in shoe making, it is sometimes desirable to prepare hides or skins of uniform thickness, which may require shaving the entire surface of a skin as distinguished from the more usual practice of 35 shaving only in selected spots. On the other hand, the old type of shaving machine designed for spot shaving, and dependent wholly upon the weight of the operator applied to the treadle, is not well adapted for 40 shaving an entire skin or hide to a uniform thickness, and in using such machine for this latter purpose it may be necessary to shave the hide several times in order to reduce it to the uniform thickness desired. 45 Moreover, even for spot shaving, the old type of machine is not altogether satisfactory by reason of the complexity of connections between the actuating treadle and the bed or feed roll operated thereby, the large number 50 of joints producing a cumulative lost motion which makes accuracy of operation difficult

while the usual mode of applying the pressure to the feed roll is wasteful of the operator's strength.

I am aware that certain attempts have been made to force the feed roll toward the 55 cutter by power actuated means, as for example a crank, in order to hold the feed roll at the proper distance from the cutter and with the necessary resistance to permit the hide to be shaved in a single pass between the roll and cutter, but in all such prior attempts, so far as is known to me, the feed roll, as in the old foot power machine, has been mounted at the upper end of a pivoted support and the force for moving the support has been 60 applied through a system of levers or the like at a point below the axis of the support, and this indirect application of the force through parts which yield or spring, or through joints which develop wear, always causes a certain degree of lost motion. Since the thickness dimension of the hide is relatively small, it results from such previous constructions that although, theoretically, the hide should be reduced to a uniform 65 thickness, it is not so reduced as a matter of fact, but presents variations in thickness from end to end. A further result is that hides are often shaved more heavily than is necessary, due to the necessity of over-adjustment of the parts in the attempt to secure 70 uniformity. Moreover, since such power operated machines are always positive in action, they are not available for use in spot shaving, which is still employed in dealing 75 with many kinds of leather.

In accordance with the present invention I provide means adapted optionally either to hold the feed roll unyieldingly and with the greatest accuracy at a fixed distance from the cutter during the cutting operation and which under such circumstances is positive in its action and during the cutting operation is wholly independent of force exerted either by the operator or by the driving power of the mechanism, or alternatively to permit the application of a yielding and varying pressure during cutting as in the older types of machine. This holding means is very simple and inexpensive to construct; 80 85 90 95 100

it can be applied to existing machines, and while not ordinarily subject to wear or lost motion by reason of multiplicity of joints or the like, is provided with means for taking up any such slight wear as may develop.

5 In the accompanying drawing:

In the drawing, Fig. 1 is a front elevation, partly in section, showing such portions of a leather shaving machine of well-known type 10 as is necessary to show the relation of the present invention thereto;

Fig. 2 is a fragmentary vertical section substantially on the line 2—2 of Fig. 1; and

15 Fig. 3 is a fragmentary plan view, to larger scale, substantially on the line 3—3 of Fig. 2, but omitting certain parts.

Referring to the drawing, the main frame of the machine is indicated as comprising the left-hand and right-hand upright frame members 1 and 2 which may be united in any usual manner to form a rigid support for the operating parts. The frame members 1 and 20 2 support bearings in which the shaft of a rotary shaving cutter 3 is mounted, such shaft being driven in any suitable manner 25 from a proper source of power. The cutter 3 may be of any desired type, preferably employing a plurality of blades. The machine may also comprise the usual grinding wheel 30 4 for sharpening the blades of the cutter.

At a suitable point, preferably between the vertical plane of the cutter axis and the front of the machine, I arrange a horizontal shaft 5 in the frame members 1 and 2, and on this shaft I mount an oscillatory frame which carries the support for the feed roll. Preferably, this frame comprises the spaced side members 6 and 7 and the upper transverse bar 8. The bar 8 is furnished with a centrally disposed swivel stud or bolt 9 (Fig. 2) which passes through an opening in the horizontal base member 10 of the feed roll support. Near its opposite ends, the upper member 8 of the frame is furnished with forwardly 45 projecting brackets 11 carrying adjustable stop screws 12 adapted to engage the member 10 near the opposite ends of the latter respectively, and thus to determine its angular adjustment about the stud 9.

50 The support 10 is provided at its opposite ends with upright bracket members 10^a and 10^b having aligned journal openings for the ends of a shaft carrying the feed roll 13. In the normal operative positions of the 55 parts the axis of the feed roll is preferably disposed substantially in the same horizontal plane as the axis of the cutter, the feed roll 13 being disposed in front of the cutter.

60 In order to limit movement of the feed roll support away from the cutter, I prefer to provide brackets 14 and 15 projecting from the frame members 1 and 2 respectively, said brackets carrying adjustable stop screws 16 and 17 adapted to engage the mem-

bers 6 and 7 respectively of the feed roll supporting frame. In order automatically to swing the feed roll away from the cutter when the retaining means hereinafter described is released, I provide the frame members 6 and 7 with downwardly directed tails 18 and 19 respectively, to which are secured the forward ends of springs 20 and 21, whose rear ends are attached to pins 22 and 22^a, respectively, projecting from the frame members 1 and 2. Thus, by proper adjustment of the screws 16 and 17, the amount of separation of the feed roll from the cutter for the introduction of work between them may be adjusted, while by adjustment of the screws 12 the axis of the feed roll may be brought into accurate parallelism with the axis of the cutter.

For moving the bed or feed roll 13 toward the cutter and for positively and unyieldingly holding it in operative position, I provide a toggle mechanism comprising the link 23 (Figs. 2 and 3) having at its rear end a sleeve 24 which receives a shaft 25 secured at its opposite ends in the end members 10^a and 10^b above referred to. A second toggle link 26 is pivotally united to the forward end of the link 23 by a pivot pin 27 so as to form a knuckle joint between the two links. The forward end of the sleeve 26 is provided with a cylindrical portion 28 having conical sockets in its outer ends adapted to receive conical pintle pins 29 and 30 having screw threaded engagement with openings in upstanding brackets carried by a slide member 31. This slide member rests upon the flat upper surface of a fixed table 32 extending between the frame members 1 and 2, and fixedly secured to the latter, as by means of bolts 33 (Fig. 3). The table 32 comprises an upstanding flange 34 forming a fixed abutment disposed forward of the toggle mechanism and having a vertical slot 35 in which is seated a screw-threaded shouldered stud 36 having a polygonal head and whose threaded end engages a threaded socket in slide 31. Rotation of the stud thus adjusts the position of the slide 31 on the table 32 and thus changes the position of the front pivotal axis of toggle link 26.

One of the toggle links, for example, the link 26 is provided with a boss or projection 37 at its under side and at a point near the pivot pin 27, such boss being adapted to engage an adjustable stop screw 38 (Fig. 2) having threaded engagement with an opening in the table 32. This stop screw is intended to be so adjusted that after the pivot pin 27 of the toggle device has moved downwardly slightly below the dead center line defined by the shaft 25 and the pins 29 and 30, its further downward movement is stopped by engagement of the lug 37 with the pin. In this position with the pivot 27 slightly below the dead center position, the toggle

locks the feed roll support unyieldingly against forward movement.

For actuating the toggle device, I provide a connecting rod 39, whose upper end engages the pivot pin 27 (the links 23 and 26 preferably having registering openings for the reception of the upper end of the rod 39). The lower end of this rod is secured to a treadle 40 mounted at its rear end upon a rod 10 41 and having a foot rest 42 at its forward end.

Preferably the feed roll support carries the transverse rod 43 which supports an apron 44 extending forwardly and downwardly so as 15 to protect the operator from contact with the adjusting screw 36 and adjacent parts, and serving as a support for that portion of the work which is forward of the feed roll.

In operation, it being assumed that the 20 feed roll 13 has been swung forwardly away from the cutter, and that the stud 36 has first been properly adjusted to attain the desired depth of the cut, the operator advances the end of the hide or skin into the space between 25 the feed roll or cutter and then by depressing the treadle 42, straightens the toggle so as to force the feed roll toward the cutter. As the pivot 27 passes down below the line of dead centers, further movement is limited by the 30 stop 38 and as the toggle is now slightly broken in a downward direction, the feed roll is unyieldingly locked at a fixed and predetermined distance from the cutter. The operator may now remove his foot from the 35 treadle and devote his entire attention to directing the material into the bite between the feed roll and cutter. The feed roll may be driven by power, if desired, in any usual manner and as the work passes between the feed 40 roll and cutter, it is shaved to a uniform thickness. When the operation is completed, the feed roll may be released by lifting the treadle slightly by means of the toe, the springs 20 and 21 completing separation of 45 the feed roll from the cutter.

It will be noted that the toggle is interposed directly between the fixed abutment 34 and the feed roll support at a point well above the pivot 5 about which the support oscillates 50 and in fact very closely adjacent to the horizontal plane defined by the axis of the cutter. The toggle thus exerts its force or pressure at a point close to the operative position of the feed roll so that there is substantially no 55 possibility that the spring of the parts will allow the feed roll to move back from its operative position. While, as just described, the toggle may be moved down to its lower limit, thus locking the feed roll at a fixed 60 distance from the cutter in order to shave a hide to a uniform thickness, it is evident that if the operator desires to use the machine for shaving a hide only at selected spots or areas, it is equally useful for this purpose, since so 65 long as the toggle is not depressed below the

line of dead centers, the feed roll is free to move back and forth in accordance with varying foot pressure as in the older machines, but with a decided improvement in operation due to greater accuracy and the better 70 mechanical advantage afforded for transmitting the foot pressure to the feed roll. Moreover, the movable parts necessary to secure the desired result are reduced substantially to a minimum, so that there is but little possibility of lost motion of appreciable amount and if such lost motion should develop through long use, it may readily be compensated for by the adjustable pintle pins 29 and 75 30.

While I prefer to employ a feed roll support which is pivoted to swing, I contemplate that the feed roll support may be movably mounted in any desired manner as, for example, upon a suitable sliding carriage, and further that changes in details of construction and relative location of parts may be made without departing from the spirit of 80 the invention.

I claim:

1. A leather shaving machine comprising a rotating cutter, a feed roll support arranged to swing toward and from the cutter about an axis below the cutter, a hard surfaced feed roll mounted upon the support 90 above said axis, the feed roll being normally spaced from the cutter, and roll controlling means operative to move the feed roll toward the cutter and to lock the support rigidly in position with the feed roll in operative relation to the cutter whereby to prevent the feed roll from yielding away from the cutter during the shaving operation, said roll controlling means comprising a fixed abutment, and movable means reacting directly 95 against the abutment, and also against the support at a point above said axis and closely adjacent to the feed roll.

2. A leather shaving machine adapted optionally to shave a hide to a uniform thickness throughout its entire area or to shave the hide at selected spots, said machine comprising a rotating cutter, a hard surfaced feed roll, and foot actuated means operative to hold the roll unyieldingly at a definite 110 and predetermined distance from the cutter during the cutting operation or alternatively to permit the roll to move yieldingly toward and from the cutter during the cutting operation, said foot actuated means comprising a 115 movable part and a rigid abutment with which said part directly reacts.

3. A leather shaving machine comprising a rotating cutter, a movable hard surfaced feed roll support, a feed roll carried by the support, and means for applying force to the support at a point closely adjacent to the feed roll for urging the feed roll in a substantially horizontal direction toward the cutter during the cutting operation, said force 125 130

- 5 applying means being operative to lock the roll unyieldingly at a predetermined distance from the cutter, or alternatively to permit the roll to move toward and from the cutter during the cutting operation, said force applying means comprising a rigid abutment and movable parts interposed directly between the abutment and support and reacting directly against the abutment.
- 10 6. A leather shaving machine comprising a frame, a rotary cutter journaled therein, a hard surfaced feed roll bodily movable toward and from the cutter, means for supporting the feed roll, a rigid abutment, means normally holding the roll away from the cutter, and means reacting directly against the abutment and roll supporting means respectively operative to hold the roll unyieldingly in operative relation to the cutter during the shaving operation.
- 15 7. A leather shaving machine comprising a frame, a cutter carried thereby, a feed roll bodily movable toward and from the cutter, a movable support for the feed roll, a rigid abutment, and a toggle directly interposed between the abutment and support and operative to move the roll toward the cutter, said toggle engaging the support at a point adjacent to the path of movement of the axis of the feed roll.
- 20 8. A leather shaving machine comprising a cutter, a feed roll having its axis substantially parallel to the axis of the cutter, a feed roll bodily movable toward and from the cutter, a movable support for the feed roll, a rigid abutment disposed in a plane closely adjacent to the plane defined by the axes of the cutter and feed roll when the latter is in operative position, and means directly interposed between said abutment and the roll supporting means for exerting force to move the support bodily toward the cutter.
- 25 9. A leather shaving machine comprising a frame, a rotary cutter journaled therein, a feed roll which is bodily movable toward and from the cutter, a movable support for the feed roll, a rigid abutment disposed in front of the feed roll support, and means interposed between the abutment and support for moving the support toward the cutter and for locking it rigidly in a predetermined operative position relative to the cutter.
- 30 10. A leather shaving machine comprising a cutter and a hard surfaced feed roll, said cutter and roll being of such length as to admit an entire skin between them, means for supporting the roll for bodily movement toward and from the cutter, and manually actuated means for unyieldingly retaining the roll at a predetermined distance from the cutter during the cutting operation whereby a skin may be shaved to predetermined thickness in a single pass between the cutter and feed roll.
- 35 11. A leather shaving machine comprising a frame, a rotary cutter journaled therein, a feed roll bodily movable toward and from the cutter, a movable support for the feed roll, a rigid abutment disposed substantially in the path of movement of the feed roll axis, and a toggle interposed between the abutment and support, said toggle reacting directly against the abutment and being operative to move the support toward the cutter, and operative to limit movement of the toggle in one direction.
- 40 12. A leather shaving machine comprising a frame, a rotary cutter journaled therein, a feed roll bodily movable toward and from the cutter, a movable support for the feed roll, a rigid abutment disposed substantially in the path of movement of the feed roll axis, and means interposed between the abutment and support operative to hold the feed roll unyieldingly at a fixed and predetermined distance from the cutter during the cutting operation.
- 45 13. A leather shaving machine comprising a rotating cutter, a feed roll support arranged to swing about an axis in an arcuate path toward and from the cutter, a feed roll mounted upon the support at one side of said axis, and mechanism, including a rigid abutment and means reacting directly thereagainst, operative to move the support toward the cutter and to lock it unyieldingly in predetermined position, said means engaging the support at the same side of the axis at which the feed roll is mounted.
- 50 14. A leather shaving machine comprising a frame, a cutter journaled therein to rotate about a substantially horizontal axis, a feed roll movable substantially horizontally toward and from the cutter, and means for supporting the feed roll, a rigid abutment adjacent to the plane defined by the axes of the cutter and feed roll, and means interposed between the abutment and feed roll supporting means for temporarily holding the feed roll unyieldingly at a fixed and predetermined distance from the cutter.
- 55 15. A leather shaving machine comprising a frame, a cutter journaled therein to rotate about a substantially horizontal axis, a feed roll movable substantially horizontally toward and from the cutter, means for supporting the feed roll, a rigid abutment ad-

10 jacent to the plane defined by the axes of the cutter and feed roll, a toggle comprising a link connected to the abutment, a second link connected to the support at a point adjacent to the axis of the feed roll, a pivot uniting the links, a foot treadle, means for transmitting movement from the treadle to the toggle for moving the toggle, and stop means for limiting relative movement of the toggle links in one direction.

15 15. A leather shaving machine comprising a frame, a cutter journaled therein to rotate about a substantially horizontal axis, a feed roll movable substantially horizontally toward and from the cutter means for supporting the feed roll, a rigid abutment, a toggle interposed between the abutment and support, one end of said toggle engaging the feed roll supporting means at a point adjacent to the feed roll axis, means for swinging the toggle toward and through the dead center position, whereby to move feed roll into operative relation to the cutter, and means operative to limit movement of the toggle 20 past the dead center, whereby to hold the feed roll unyieldingly in operative relation to the cutter.

25 16. A leather shaving machine comprising a cutter and a hard surfaced feed roll, said feed roll and cutter being of a length sufficient to admit a whole skin between them, means for supporting the roll for bodily movement toward and from the cutter, means for unyieldingly retaining the roll 30 at a predetermined distance from the cutter during the cutting operation, and means for varying such predetermined distance between the cutter and feed roll whereby an entire skin may be shaved to an adjustably 35 predetermined thickness in a single continuous pass between the feed roll and cutter.

40 17. A leather shaving machine comprising a frame, a cutter carried thereby, a hard surfaced feed roll bodily movable toward and from the cutter, means for supporting the feed roll, an abutment, a toggle linkage directly interposed between the abutment and the feed roll supporting means, said toggle being operative to move the feed roll toward the cutter, and means operative to hold the abutment rigidly fixed in any of a plurality of predetermined positions of adjustment.

45 18. A leather shaving machine comprising a frame, a rotary cutter journaled therein, a feed roll bodily movable toward and from the cutter, a movable support for the feed roll, a rigid abutment disposed substantially in the path of movement of the feed roll axis, toggle means connecting the abutment and support, said toggle means being operative to move the support toward the cutter, a foot treadle, means connected to the 50 treadle for actuating the toggle, and stop 55

means operative to limit movement of the toggle.
